[57] CLAIM

The ornamental design for an adjustable pipe joint, substantially as shown and described.

DESCRIPTION

FIG. 1 is a perspective view taken from the top, front and left side of an adjustable pipe joint showing our new design;

FIG. 2 is a left side elevation thereof;

FIG. 3 is a rear elevation thereof;

FIG. 4 is a front elevation thereof;

FIG. 5 is a right side elevation thereof;

FIG. 6 is a top plan view thereof;

FIG. 7 is a bottom plan view thereof;

FIG. 8 is another perspective view taken from the top, front and left side thereof showing the pipe joint in an adjusted position.

The fragmentary broken line showing of pipes in FIGS. 1 and 8 are for purposes of illustration only.
